UNITED STATES PATENT OFFICE

137,706

DESIGN FOR AN ERASER OR THE LIKE

George L. Estes, Wichita, Kans.

Application September 24, 1943, Serial No. 111,197

Term of patent 14 years

(Cl. D74—7)

To all whom it may concern:

Be it known that I, George L. Estes, a citizen of the United States, residing at Wichita, in the county of Sedgwick and State of Kansas, have invented a new, original, and ornamental Design for an Eraser or the like, of which the following is a specification, reference being had to the accompanying drawing, forming a part thereof.

Fig. 1 is a side view of an eraser or the like showing my new design.

Fig. 2 is an edge elevational view thereof.

I claim:

The ornamental design for an eraser or the like, substantially as shown.

GEORGE L. ESTES.
